UNITED STATES PATENT OFFICE

WILLIAM P. JOHNSON, OF DES MOINES, IOWA

TUB SUPPORT

Application filed May 6, 1931. Serial No. 535,403.

The object of this invention is to provide an improved support for a laundry tub whereby the tub is supported at a suitable elevation and is readily movable for use in carrying out domestic laundry operations.

More specifically, the object of this invention is to provide improved means for bracing the lower ends of the legs of an elevated tub.

10 Still another object is to provide an improved and outstandingly simple method of assembling braces relative to legs of an elevated tub in conjunction with casters for the legs.

15 With these and other objects in view my invention consists in the construction, arrangement and combination of the various parts of my device, whereby the objects contemplated are attained, as hereinafter more fully set forth, pointed out in my claims, and illustrated in the accompanying drawings, in which:—

Figure 1 is a perspective view of a tub having a three-leg support embodying my invention.

20 Figure 2 is an enlarged section on the line 2—2 of Figure 1, illustrating particularly the method of assembling a leg, caster and braces.

Figure 3 is a horizontal section illustrating 30 a method of bracing a four-leg tub support.

Figure 4 is a perspective view of one end portion of a brace employed in carrying out my invention.

It has been common practice recently to 35 provide means for supporting ordinary wash tubs by means of legs, usually equipped with casters, in order to provide a convenient portable elevated tub for domestic laundry purposes.

40 At times it has been found difficult to properly attach and brace the legs which are employed for the support and to construct a suitable support having sufficient strength and rigidity without involving too much expense.

45 My present invention relates particularly to a simple and effective means for bracing the lower ends of the legs.

In the accompanying drawing I have shown a sheet metal tub 10 of common form 50 which may be equipped with an outlet hose 12

communicating with its bottom for discharging water from the tub.

A plurality of legs 14 are provided and are uniformly spaced around the tub. As here shown, the legs 14 are made of structural angle iron and in the type shown in Figure 1 they are three in number. The legs 14 may be attached to the tub in any suitable manner.

In accordance with my invention each leg 14 is pressed or rolled at its lower end to provide a substantially cylindrical bearing portion 16 which is preferably arranged in substantially vertical position, although the major portions of the legs may be obliquely arranged in spreading relation.

A caster socket or sleeve 18 is mounted in each of the bearing portions 16 and firmly held therein by frictional contact. The socket member 18 is provided at its lower end with an enlargement 19 which may be in the nature of a disc or shoulder thereon. Each caster socket or sleeve 18 is adapted to receive the stem 20 of a swivel caster 22.

A plurality of braces 24 are provided for connecting the lower end portions of the legs 25 in mutually bracing relations.

Each brace 24 preferably is formed of a strip of metal of suitable weight and the major portion of each brace preferably is formed concavo-convex in cross section to 30 lend strength and rigidity.

Each brace 24 has a flattened portion 26 at each end formed with a circular opening 28. The openings 28 are of sufficient size to readily receive one of the caster sockets 18 35 employed for the legs.

In assembling the casters and braces to the lower ends of the legs, the sockets 18 are inserted through the openings 28 of the braces before being placed in position in the bearing portions 16 of the legs. The enlargement 19 on the socket member thus engages beneath and provides a support for the brace.

In the event it is desired to arrange the braces 24 in series of polygonal form with 40 relation to the legs, the ends 26 of two of the braces may be arranged in overlapping relation and the socket 18 inserted through the openings 28 of both of said braces. This arrangement is particularly desired when 45

the tub is provided with three legs 14 as shown in Figure 1 and the overlapping relation of the braces also is illustrated also in Figure 2.

In the event the tub is provided with four legs it may be convenient to employ only two of the braces 24 and to arrange them in diagonal formation as shown in Figure 3. In this event each leg will have only one brace associated with its lower end and the two braces will cross at the center of the structure where they may be interconnected by any suitable means such as a bolt 30.

This method of forming and mounting the braces provides a simple and very inexpensive bracing structure which is highly effective for rigidly interconnecting the lower ends of the legs and providing a rigid form of tub support.

It will be understood that it is a simple operation to manufacture the braces 24 with their flat apertured ends 26 and that a relatively small amount of material is required therefor. The outstanding advantage of this type of bracing, however, lies in the ease and simplicity of the assembling operation. It is desirable to employ the casters for convenience in moving the tub about on a floor and these casters according to my invention have the additional function of providing means for attaching braces to the legs. This is accomplished, as before stated, merely by inserting a caster socket 18 through an opening 28 of one or more of the braces before mounting the socket in its position in the leg. By this method no additional cost is involved for labor in the assembling operation nor for materials in effecting a suitable and stable connection of the braces to the

legs. It is obvious that the braces cannot become detached from the legs so long as the caster sockets are in place. To this end the caster sockets 18 preferably fit very snugly in the bearing portions 16, which may be formed in such manner as to be capable of some spreading movement when the tight fitting caster sleeves are inserted therein.

I claim as my invention:—

1. In a support of the type including a plurality of legs, each leg formed with a socketed opening at its lower end, a caster socket member adapted to be mounted in said socketed opening and arranged to receive a caster stem, a leg brace formed of a strip of metal formed substantially concavo-convex in section and flattened at each end and having at each flattened end an opening through which a socket member is inserted before mounting in its socketed opening, for thereby conjunctively assembling the socket member and brace to the leg.

2. In a device having a plurality of spaced supporting members and a caster connected with each of said members for swiveling movement, a bracing structure comprising brace bars arranged to connect said supporting members in pairs, each brace bar being formed of a strip substantially concavo-convex in section and having substantially plane end portions, each of said end portions being formed with an opening therethrough to receive a portion of the caster before it is inserted in its supporting member, for conjunctively assembling the caster and brace bar to the supporting member.

WILLIAM P. JOHNSON.
